PHOTOGRAPHIC PLATE OR FILM FOR THE
INVESTIGATION OF BODIES OR SUB-
STANCES BY MEANS OF NEUTRONS

Hartmut Israel Kallmann, formerly known as
Hartmut Kallmann, Berlin-Charlottenburg,
Ernst Kuhn, Berlin, and John Eggert, Leipzig,
Germany; vested in the Alien Property Custo-
dian

Application March 16, 1939, Serial No. 262,306
In Hungary March 23, 1938

1 Claim. (Cl. 95—8)

Bodies or substances including for example living tissues, which scatter or absorb neutrons, may be investigated by means of neutrons, and preferably by means of slow neutrons (that is to say neutrons the "de Broglie" wave of which is approximately equal to or larger than the diameter of the nucleus of the substance being examined) by exposing the substance to the neutrons and causing the neutrons which emerge from the substance to act on a layer of a material in which a reaction takes place in which are produced heavy charged particles, or positively or negatively-charged electrons, the heavy particles or electrons being caused to act on an adjacent photographically-sensitive layer directly as described in the specification of application No. 197,929, now U. S. Patent No. 2,186,757, or on a photographically-sensitive layer associated with a fluorescent material as described in the specification of application No. 197,928, now U. S. Patent No. 2,188,115.

According to the invention the intermediate layer that gives off the heavy particles or the electrons, or the fluorescent material or both is or are applied to the photographically-sensitive layer in the form of a liquid which is allowed to set, the liquid comprising the intermediate layer or the fluorescent material suspended in or mixed with a binder which dissolves in solvents which do not have an adverse effect on the photographically-sensitive layer and its support or in any liquid which the photographic layer is treated with during the whole photographic process summarized as development, of reducing the activated compounds of silver and/or of dissolving the nonactivated compounds of silver.

The invention will be more particularly described with reference to the accompanying drawing in which:

Fig. 1 is a diagrammatic representation of a photographic plate or film embodying the invention; and

5 Figs. 2 and 3 are diagrammatic representations of modified embodiments of the invention.

In the figures, 2 represents a photographic emulsion and 3 represents a supporting layer. In Fig. 1, 1 is a layer comprising a substance capable of reacting with neutrons to produce charged particles, for example, a substance containing lithium or boron atoms, and a binder soluble in a solvent which does not affect the photographic emulsion or in the liquids used in the photographic development process.

10 15 In Fig. 2, 4 is a layer similar to layer 1 of Fig. 1 but containing also a fluorescent material.

In Fig. 3, 1 is a layer similar to layer 1 of Fig. 1, and 5 is a layer comprising a fluorescent material and a binder having the same properties as the binder of layer 1.

20 Having now particularly described and ascertained the nature of our said invention and in what manner the same is to be performed, we declare that what we claim is:

25 A photographic plate or film for use in the investigation of materials by means of neutrons comprising a supporting layer, a layer of photographic emulsion on said supporting layer and a layer comprising a substance capable of reacting with neutrons to generate charged particles and a binder substance, the binder substance being soluble in a liquid capable of developing the photographic layer.
